[57] CLAIM

The ornamental design for a therapeutic massager or the like, as shown and described.

DESCRIPTION

FIG. 1 is a bottom perspective view of a therapeutic massager or the like, showing my new design;

FIG. 2 is a top plan view thereof;

FIG. 3 is a bottom plan view thereof;

FIG. 4 is a side elevational view thereof, the opposite

side elevational view being identical thereof; and

FIG. 5 is a front elevational view thereof.

*Fig. 1.**Fig. 2.**Fig. 3.**Fig. 4.**Fig. 5.*
